UNITED STATES PATENT OFFICE.

ANDREW WICZIAN, OF CHICAGO, ILLINOIS.

DESIGN FOR A GLASS RECEPTACLE.

50,369.

Specification for Design. Patented Feb. 20, 1917.

Application filed November 13, 1916. Serial No. 131,158. Term of patent 7 years.

To all whom it may concern:

Be it known that I, ANDREW WICZIAN, subject of the Emperor of Austria-Hungary, residing in Chicago, in the county of Cook and State of Illinois, have invented a new, original, and ornamental Design for a Glass Receptacle, of which the following is a specification, reference being had to the accompanying drawing, forming part thereof.

Figure 1 is a side elevation, showing my new ornamental design.

Fig. 2 is a plan view, taken on the line 2—2 of Fig. 1.

Fig. 3 is a bottom view, taken on line 3—3 of Fig. 1.

I claim:

The ornamental design for a glass receptacle, as shown.

In witness whereof, I have hereunto subscribed by name this 8th day of November, 1916.

ANDREW WICZIAN.
